UNITED STATES PATENT OFFICE.

JOHN J. TOWER, OF BROOKLYN, NEW YORK.

DESIGN FOR A PADLOCK-CASE.

SPECIFICATION forming part of Design No. 18,436, dated July 3, 1888.

Application filed May 25, 1888. Serial No. 275,079. Term of patent 14 years.

To all whom it may concern:

Be it known that I, JOHN J. TOWER, of Brooklyn, in the county of Kings and State of New York, have invented and produced a new and original Design for Padlocks; and the following is a specification, reference being had to the accompanying drawings forming part thereof.

In the drawing I have represented my new and original design for padlocks by a perspective view representing the case and other parts of the lock.

Heretofore padlocks have been made which presented, when viewed in elevation, a flattened heart shape and also a circular shape having a smooth exterior surface.

The leading feature of my design for padlocks consists in the representation of a barrel the outline of which, when viewed in elevation, presents the usual appearance of a barrel, wherein the sides or staves composing the barrel and the hoops and the heads are represented by raised portions and lines.

A represents the body portion of the barrel, which is circular in general contour and tapering toward the ends; and b represents the

heads. These are also circular, and lines are shown to represent the divisions of the heads.

a represents the sides and by the longitudinal lines the barrel - staves, and c represents the hoops, and c' the end hoops, the outline of the barrel being identical in its representation with that of a real barrel.

d represents the hasp of the padlock, and e, at one end of the barrel, represents the key. The shape and configuration of the hasp and key may be varied or otherwise located than as shown without materially departing from my new and original design, the essential feature of which is a representation of a barrel for a padlock.

I claim as my invention—

The design for a padlock-case herein shown and described, the same consisting of the barrel-shaped body A, having the hasp or loop d projecting centrally, and having the slot b in one head, substantially as specified.

Signed by me this 23d day of May, 1888.
JOHN J. TOWER.
